UNITED STATES PATENT OFFICE.

EDGAR E. BROSIUS, OF PITTSBURGH, PENNSYLVANIA.

MACHINE FOR CHARGING SLABS, BILLETS, &c.

1,313,619.

Specification of Letters Patent. Patented Aug. 19, 1919.

Application filed May 25, 1918. Serial No. 236,646.

To all whom it may concern:

Be it known that I, EDGAR E. BROSIUS, a citizen of the United States, residing at Pittsburgh, in the county of Allegheny and State of Pennsylvania, have invented a new and useful Improvement in Machines for Charging Slabs, Billets, &c., of which the following is a full, clear, and exact description, reference being had to the accompanying drawings, forming part of this specification, in which—

Figure 1 is a sectional elevation of a machine embodying my invention.

Fig. 1^a is a diagrammatic view illustrating one way in which the peel may be suspended.

Fig. 2 is a similar view of a part of the machine on a larger scale and with the movable parts in different positions.

Fig. 3 is a section on the line III—III of Fig. 1, and

Fig. 4 is a section on the line IV—IV of Fig. 2.

My invention is designed to provide a simple and efficient machine for charging slabs, billets and the like into furnaces; and more particularly, to provide a machine of this character which is hand manipulated and which can be operated by any usual crane mechanism. Also to provide a machine of this character by which the slabs and the billets can be readily and easily manipulated and brought into proper position.

The nature of my invention will be best understood by reference to the accompanying drawings in which I have shown a preferred embodiment thereof, and which will now be described, it being premised, however, that various changes can be made in the details of construction and arrangement of the parts without departing from the spirit and scope of my invention, as defined in the appended claims.

In these drawings the numeral 2 designates the peel of the charging machine or device, and which is shown as consisting of a tubular member journaled in a front bearing block 3 provided with roller or other suitable anti-friction bearings 4. The rear end portion of this peel member is connected by a tubular member 5 with the hub portion 6 of a rear bearing member 7, the latter being journaled on the anti-friction bearings 8 in the suspension block 9. The block 9 is designed to be suspended from an

overhead crane trolley (not shown) or from a trailer attached to said trolley, as indicated by the suspension chain 10. The front bearing block 3 is suspended, as indicated at 11, from the hook of any trolley of an overhead traveling crane (not shown), this suspension point being a movable point which allows of any desired angle of operation.

12 designates a gear casing having the hinged cover portion 12^a and which is carried by a hub member 13 mounted in the forward end of the peel 2 on the anti-friction bearings 14. 15 designates a screw which extends upwardly into the gear casing 12 in which it engages a sleeve-nut 16 having secured thereto a beveled gear wheel 17. Said screw extends downwardly through a guide block 18 and has an eye 19 at its lower end which carries a pin 20. 21 and 22 designate two links or toggles which, at one end portion, engage the pin 20, and which at their opposite end portions engage respectively the pins 23 and 24 which are seated in oblique slots 25 in the guide block 18. 26 designate tong socket members which are respectively carried by the pins 23 and 24, these socket members extending in opposite directions through openings in the guide block 18 and crossing each other within said block. Secured to each socket member is a tong member 27, the respective jaws 28 of said members being properly positioned to engage the opposite ends of a slab or billet, such as indicated in dotted lines at X.

29 is a beveled gear wheel whose teeth engage the teeth of the beveled gear wheel 17 before referred to, and which is rigidly secured to the end of a torsion rod 30, which extends backwardly through the peel and has an extension 31 at its rear end which extends rearwardly through the rear bearing and has secured thereto a hand wheel 32. The gear wheel 29 is shown as threaded on the end of the torsion rod 30 and is prevented from turning relatively thereto by means of the small screw 33. 34 indicates anti-friction bearings for the torsion rod and its extension. The gear wheel 17 is provided with anti-friction bearings 35 on the crosshead 36. 37 designates a counterweight box, which is hung from the rear suspension block 9, and which is, when in use, weighted to a sufficient extent to balance the weight on the tongs and tong centers, 110

thereby permitting the parts to move freely on their respective bearings. 38 is a ratchet wheel, which is fixedly secured to the torsion rod extension 31, and has its teeth engaged by a pawl 39, which is pivoted to the heel portion 40 of a pawl lever 41 mounted on a bracket 42 secured to the bearing member 7. As will appear from Fig. 3, the pawl 39 and the pawl lever 41 are so arranged as 10 to give the pawl a toggle-action which increases its locking power on the ratchet wheel. 43 is a similar ratchet wheel secured to the peel extension 5 and having its teeth engaged by a pawl 44 mounted on the bracket 15 45, also carried by the rear suspension block 9. This last named pawl and ratchet device is a precaution against the possibility of the whole peel turning on its roller bearings in a manner to tend to release the tongs. 20 The operation is as follows:

The parts being in the position shown in Fig. 2, when the hand wheel 32 is turned in a clockwise direction, the screw 15 will be actuated to in turn actuate the links 21 25 and tongs 27 to close the latter on the slab or ingot in the manner shown in Fig. 1. When the tongs are thus closed an extra pull on the hand wheel will set the pawl 39 on the ratchet 38, so as to maintain a constant pressure on the tongs sufficient to prevent their tripping, this being due to the spring in the rod 30. The charging device with the ingot is then lifted and moved by the overhead crane to any desired point. If 30 it is desired to turn the ingot in a horizontal plane about the vertical axis of the screw 15, this can be effected by turning the hand wheel 32 in a clockwise direction. Inasmuch as the tongs are closed upon the ingot, further relative movement of the nut and 35 screw is prevented, and the entire peel will rotate on its front and rear bearings. The weight of the ingot on the screw, however, maintains the latter in its vertical position, the hub portion 13 of the gear casing turning 40 on the anti-friction bearings 14. The gearing in the gear casing is thereby caused to act in the manner of a differential gear to cause a rotation of the screw and nut, 45 and thereby turn the ingot to the desired angle. The pawl 44, when employed, acts 50 as a safeguard to prevent any tendency of the entire peel to turn in an anti-clockwise direction on its bearings and thus tend to 55 release the grip of the tongs.

The advantages of my invention result from the provision of a simple and comparatively inexpensive charging device which can be hand-manipulated and operated by ordinary crane mechanism, and which is comparatively inexpensive.

I claim:

1. A charging device of the character described, comprising a peel, suspended bearings in which the peel is mounted for ro-

tary movement, tong members, a screw operatively connected with the tong members, gearing journaled on the peel for actuating the tong members, and an actuating connection for the gearing extending axially 70 through the peel, substantially as described.

2. A charging device of the character described, comprising a peel, front and rear bearings therefor, one of said bearings having a relatively fixed point of suspension, 75 and the other bearing having a movable point of suspension, tong members supported on the peel, an actuating screw operatively connected to said members, gearing for actuating said screw, an actuating rod 80 for said gearing extending axially through the peel, and counterbalancing means suspended from the peel, substantially as described.

3. A charging device of the character described, comprising a tubular peel, front and rear bearings in which the peel is rotatably mounted, said bearings having means for suspending the peel from overhead points of support, a gear casing journaled on the peel, an actuating screw extending within the gear casing, tongs operatively connected with said screw, a nut in the gear casing engaging the screw, a gear wheel secured to said nut, and a rotatable 90 actuating rod extending through the peel and carrying a gear wheel to engage the wheel on said nut, substantially as described.

4. A charging device of the character described, comprising a hollow peel, front and rear bearings in which the peel is rotatably mounted, said bearings having means for suspending the peel from overhead points of support, a gearing casing rotatably mounted 100 on the peel, tong members, an actuating screw extending within the gear casing, links connecting the screw with the tong members, a nut for actuating the screw, a gear wheel secured to said nut, an actuating 105 rod extending axially through the peel and provided with a hand wheel at its rear end, and a gear wheel carried by said rod and engaging the first named gear wheel within the gear casing; substantially as described.

5. A charging device of the character described, comprising a hollow peel, front and rear bearings in which the peel is rotatably mounted, said bearings having means for 120 suspending the peel from overhead points of support, a gear casing rotatably mounted on the peel, tong members, an actuating screw extending within the gear casing, links connecting the screw with the tong members, a 125 nut for actuating the screw, a gear wheel secured to said nut, an actuating rod extending axially through the peel and provided with a hand wheel at its rear end, and a gear wheel carried by said rod and engag 130

ing the first named gear wheel within the gear casing, together with counter-balancing means for the peel, substantially as described.

5 6. Charging mechanism of the character described, comprising a rotatable peel, tongs carried by said peel, an actuating screw for the tongs, gearing for actuating said screw, a rotary actuating connection for said gearing, and means for locking the peel and actuating connection to each other, said parts being arranged to permit rotary movement of said screw and tongs when the peel and actuating connection are so locked, substantially as described.

10 7. Charging mechanism of the character described, comprising a rotatable peel, bearings in which said peel is mounted, said bearings having means for suspending the 20 peel from overhead points of support, a gear casing rotatably mounted on the peel, an actuating screw extending within the gear casing, tongs operatively connected with said screw, a nut engaging the screw, a bevel 25 gear wheel carried by the nut, another bevel gear wheel engaging the first named wheel, an actuating rod for the bevel gear extending through the peel and provided with an actuating device, and means for locking the 30 actuating rod and peel against relative movement, substantially as described.

8. The combination with a horizontal peel, of tongs suspended from said peel, and means for rotating the tongs about a vertical 35 axis passing through the tong center, substantially as described.

9. In apparatus of the character described, the combination with a horizontal peel, of tongs suspended from the outer end 40 portion of the peel, and means for rotating the tongs about a vertical axis adjacent to the point of support of the tongs on the peel, substantially as described.

10. In apparatus of the character described, the combination with a horizontal 45 peel, of tongs suspended from the outer end portion of the peel, and means for rotating the tongs about a vertical axis passing through the center of the tongs, substantially as described. 50

11. In apparatus of the character described, the combination with a horizontal peel suspended from an overhead support, of tongs suspended from the outer end portion of the peel, and means for rotating the 55 tongs about a vertical axis which is eccentric with respect to the points of suspension of the peel, substantially as described.

12. In apparatus of the character described, a horizontally movable peel, tongs 60 swiveled to and depending from the outer end portion of the peel, and means for rotating the tongs about a vertical axis passing through the end portion of the peel from which the tongs are suspended, substantially 65 as described.

13. In apparatus of the character described, a horizontally movable peel, tongs swiveled to and depending from the outer 70 end portion of the peel, and gearing mounted on the peel and having means for opening and closing the tongs and for rotating the tongs in a horizontal plane when they are closed independently of the movement of the peel, substantially as described. 75

14. In apparatus of the character described, the combination with a horizontal 80 peel of tongs suspended from the outer end portion of the peel, and means for rotating the tongs about a vertical axis while holding the peel stationary, substantially as described.

In testimony whereof, I have hereunto set my hand.

EDGAR E. BROSIUS.
